[57] ABSTRACT

A piston pump, having at least one delivery plunger to deliver pressure fluid from a suction chamber via a working chamber into a pressure port, is provided with elastic damping elements arranged in the suction chamber to compensate for the occurring pressure pulsations.

14 Claims, 3 Drawing Sheets

FIG.1

FIG.2

FIG.3

FIG. 4

FIG. 5

PISTON PUMP

BACKGROUND OF THE INVENTION

The present invention relates to a piston pump having at least one delivery plunger delivering pressure fluid from a suction chamber via a working chamber into a pressure port. Undesirable noises are caused by pressure pulsation in such pumps. For noise reduction, it is known from DE AS 28 24 239 to direct the pressure fluid from the working chamber to the pressure port via a collecting chamber which acts as a vibration damper.

To attenuate vibrations in the suction lines, it is known to use so-called "intake air vessels". However, these intake air vessels bear the shortcoming of necessitating an enormous overall size in order to safeguard an acceptable balance between the flow speed of the suction fluid and the delivered fluid. Furthermore, they become ineffective in the event of high-vacuum venting with subsequent pressure loading.

SUMMARY OF THE INVENTION

Therefore, the instant invention has for its object to accomplish noise attenuation for piston pumps. The invention is characterized by small space requirements, while having optimum damping abilities. The invention is accomplished by simple means at low costs and lends itself to ease of maintenance. The invention is suitable for use on pumps which are vacuum-vented prior to pressure loading.

This object is achieved, according to the present invention, by arranging elastic damping elements in the suction chamber. In this way, the pressure vibrations in the suction area of the pump are compensated directly where they are caused.

A preferred embodiment of this invention provides an elastic damping element that is formed by at least one deformable shaped part which contains at least one closed gas-filled compartment. In a particularly economical embodiment of this invention, the deformable shaped part is made of closed-cell foam material or rubber. In this way, the elastic means can be easily adapted to the existing suction chamber geometry.

Another embodiment of this invention provides an elastic damping element that is a movable wall which confines a gas chamber within the suction chamber. Thus, for instance, mounting of a diaphragm into the suction area permits effective noise attenuation in a simple fashion.

Another advisable embodiment of this invention arranges the damping element as an annularly closed rubber hose. This provides a large damping surface, and the damping element can be easily inserted and held in the suction chamber. For guiding purposes and for obtaining a defined deformability, the damping element cooperates with the ring filter element. The filter element is furnished with web-like retaining arms which receive the damping element partially embracing it at a radial distance. The webs are almost evenly spaced from each other, and the wall confining the suction chamber contributes to securing the damping element in position. This ensures ease of assembly, disassembly and quick exchangeability.

Further advantageous features, as well as the function of this invention, can be understood from the following description with reference to the accompanying drawings.

BRIEF DESCRIPTION OF THE DRAWINGS

In the drawings

FIG. 1 shows the principal structure of a first embodiment of this invention,

FIG. 2 shows the design of a second embodiment of this invention,

FIG. 3 is a specific embodiment according to FIG. 1,

FIG. 4 is a full view of the damping element designed as a damping hose with connecting portions shown in partial cross-section; and

FIG. 5 is a cross-sectional view of the radial piston pump of FIG. 1.

DETAILED DESCRIPTION OF THE PREFERRED EMBODIMENTS

FIGS. 1 and 5 depicts schematically a radial piston pump 1 flanged to an electric motor 2. This radial piston pump 1 delivers fluid out of a reservoir into the pressure line 5 via the suction chamber 3 and the suction line 4.

To compensate for pulsation of the suction pressure, an elastically deformable shaped part 6 is arranged in the suction chamber 3 which is composed of foam material with closed air bubbles or gas bubbles. The geometry of this shaped part 6 is dictated by the special space conditions in the suction area of the pump. In lieu of any foam material, a shaped part can also be used which, instead of a plurality of bubbles, comprises only one or more specially shaped air compartments or gas compartments.

The embodiment shown in FIG. 2 provides a diaphragm 7 as an elastic means in the suction chamber 3. The diaphragm forms a closed compartment 8 in the suction chamber 3, that is preferably filled with air. The compressibility of the air permits compensation for suction pressure pulsations.

The inventive embodiment illustrated in FIG. 3 shows an annularly extending damping hose 9 arranged in the suction chamber 3. The damping hose 9 is fixed by the annular filter element 10 arranged in the suction chamber 3. To this end, the filter element 10 is furnished with several retaining arms 11 distributed over the periphery of the filter element partially encompassing the damping hose 9, thereby clamping it between the filter element 10 and the adjoining wall in the housing 12. The damping hose 9 is designed as a component part assembled at its two ends, or it can be composed of several segments which are put together.

FIG. 4 shows a full view of the gas-filled damping 50 hose 9. In the area of the partial cross-section, the obtuse-angularly bent connecting portion 13 is fitted into the two ends of the hose to close the gas-impermeable compartment 8 in the damping hose 9 in a pressure-fluid tight manner. Preferably, the damping hose 9 is made of rubber so that the preloading force of the expanded rubber holds the two hose ends captive on the connecting portion 13 which is chamfered like a truncated cone on both sides.

What is claimed is:

1. A piston pump having at least one delivery plunger delivering pressure fluid from a suction chamber via a working chamber into a pressure port, characterized in that at least one elastomeric damping element is arranged in said suction chamber, and that a filter element has several substantially axially extending retaining arms spread over a periphery of said filter element to cooperate with an external diameter of said at least one elastomeric damping element.

2. A piston pump as claimed in claim 1, characterised in that the elastomeric damping element is formed by at least one deformable shaped part (6, 9) which contains at least one closed gas-filled compartment.

3. A piston pump as claimed in claim 1, characterised in that the elastomeric damping element is a damping hose (9) of a preferably annular, closed configuration.

4. A piston pump as claimed in claim 3, characterised in that the damping hose (9) has an annular profiled cross-section.

5. A piston pump as claimed in claim 3, characterised in that the damping hose (9) comprises a compartment (8) filled with gas.

6. A piston pump as claimed in claim 5, characterised in that the compartment (8) is closable pressure-fluid-tightly by a connecting portion (13) which is insertable into the two ends of the damping hose (9).

7. A piston pump as claimed in claim 6, characterised in that the connecting portion (13) of the damping hose (9) has a circular cross-section and is bent preferably in an obtuse-angled manner.

8. A piston pump as claimed in claim 6, characterised in that the external diameter of the connecting portion (13) is larger than the internal diameter of the damping hose (9) mirror-symmetrically by an identical length to be inserted into the damping hose (9) on either side of its angled-off portion.

9. A piston pump as claimed in claim 6, characterised in that the external diameter of the connecting portion

(13) by approximation corresponds to the external diameter of the damping hose (9).

10. A piston pump having at least one delivery plunger delivering pressure fluid from a suction chamber via a working chamber into a pressure port, characterised in that at least one elastomeric damping element is arranged in the suction chamber, that the elastomeric damping element is a damping hose of an annular, closed configuration, and that the external diameter of the damping hose cooperates with several substantially axially extending retaining arms which are spread over the periphery of a filter element.

11. A piston pump as claimed in claim 10, characterised in that the retaining arms (11) of the filter element (10) embrace the damping hose (9) partly radially.

12. A piston pump as claimed in claim 10, characterised in that the filter element (10) cooperates with the damping hose (9) in the suction chamber (3) of the pump.

13. A piston pump as claimed in claim 10, characterised in that the filter element (10) is conformed to the shape of the damping hose and can be radially penetrated by fluid.

14. A piston pump as claimed in claim 3, characterised in that the damping hose (9), at its periphery, is in partially supporting contact with a wall confining the suction chamber (3).
